DIVIDED SKIRT

Selda K. Pierce, Brookline, Mass.

Application May 12, 1937, Serial No. 142,140

3 Claims. (Cl. 2-214)

This invention relates to women's garments and pertains more particularly to improvements in the manufacture of divided skirts of the general type shown as, "culottes". The general purpose of the invention is to provide a divided skirt which affords to the wearer the ease, comfort and masculine freedom of movement characteristic of the full-cut culotte or of other garments of this general type, while at the same time presenting 5 the style, neatness and feminine formality of the ordinary skirt.

To this end, the trunk and crotch portions of my improved garment are fashioned and manufactured in a novel way, so that the trunk or leg members substantially overlap each other at 15 front and rear, with the crotch extending in a diagonal direction in contrast to the ordinary straight front-to-rear direction of prior divided skirts. Thus, the visible vertical lines of division or openings between the trunk portions are substantially offset (one in front and the other in rear) from the median lines of the garment, as viewed from the front or rear.

The skirt material at these vertical openings or lines of division are preferably fashioned to resemble open pleats; and inverted, kick pleats, having a length and direction corresponding to said openings, are preferably formed on the respective trunk portions (one in front and the other in the rear) on the opposite side of said median lines and at an equivalent distance therefrom. As continuations of the visible openings between the trunk portions and of the aforesaid kick pleats, stitched-down pleats or 35 tucks preferably lead upward from the crotch portion of the garment to the waistband thereof. Hence, when the garment is viewed from either the front or the rear, it has the appearance of a normal skirt provided with a pair of pleats spaced on opposite sides of the center or median line thereof; and no division between the trunk portions is noticeable when the garment is suspended from its waistband or even when the wearer is standing or walking at a normal pace.

45 A recommended embodiment of my invention is illustrated in the accompanying drawings showing a divided skirt fashioned and finished as above suggested; but it will be understood that this invention is not intended to be restricted to the particular methods of manufacture or to the structural details herein described, except as the novel features of the invention are set forth in the appended claims.

In the drawings:

55 Fig. 1 is a front view of my new skirt;

Fig. 2 is a rear view thereof;

Figs. 3 and 4 are front and rear views, respectively, of assembled dress patterns which may be used in fashioning the skirt.

Fig. 5 shows said patterns opened out, flatwise; 5 and

Figs. 6 and 7 are diagrammatic sections, taken approximately on lines 6-6 and 7-7, respectively, of Fig. 1.

Referring to Figs. 1, 2 and 6, the upper portion 10 of my improved garment is formed in the manner of an ordinary skirt, and has a waistband 11 and a side placket 12 which may be closed by ornamental buttons 13 or other fastenings. Darts 14 may be provided at the hip portions, as usual. 15 As indicated above, stitched-down vertical pleats or tucks 15 and 15', 16 and 16' are formed at the front and rear, respectively. These four pleats may be substantially equidistant from each other, and each pair should be substantially at 20 the same distance from the imaginary median line of the garment as the other pair, as shown on the drawings.

The lower part of the skirt is divided into a pair of trunk or leg portions 17 and 18, as best 25 indicated in Figs. 6 and 7 which show the diagonal direction of the crotch 19, and the relative location of the visible openings or slits 20 and 20' between said portions at the front and rear of the garment, respectively. The pleated visual effect along said slits is produced by the formation of pleats 25 and 25' on the respective leg portions, as best shown in Fig. 7, these pleats being a continuation of the tucks 15 and 15' respectively at the upper portion of the garment.

Somewhat similarly, inverted kick pleats 26 and 26' are provided down each leg portion, as continuations of the tucks 16 and 16', the kick pleats presenting substantially the same visual appearance as the folded material at the corners 22 and 22' in association with the pleats 25 and 25', at the slits 20 and 20'. It will be understood that the pleats and folds above described are pressed flat, in finishing the garment, and it will be appreciated that the front and rear views of the 45 finished skirt are approximately the same.

My divided skirt may be made from any desired textile or other flexible material, and may comprise as many individual pieces of material as may be necessary or desirable in fabricating the 50 garment. As illustrated, each trunk or leg portion consists of two pieces of fabric, joined at the side seams 27 and 28 and at the inseams 29 and 30 (Fig. 7), the former continuing upwardly to the waistband of the garment, and the latter 55

joining and terminating at the crotch 19, as shown at 31 (Fig. 6).

Suitable patterns for making the garment herein described are shown in Figs. 3 to 5, on which the numeral refers to the corresponding parts of the finished skirt.

I claim:

1. A divided skirt comprising an upper portion shaped to fit the waist and hips of the wearer, and a pair of depending trunk portions joined at the crotch of the garment, each of said trunk portions comprising two pieces of material joined by seams extending, respectively, along the side of the garment on the outside of the trunk portion, and along the center of the trunk portion at the inside thereof, and said crotch extending in a diagonal direction from front to rear of the garment so that the trunk portions substantially overlap each other, both front and rear, the visible lines of the division therebetween being substantially offset from the median line of the garment, so that the garment presents the appearance of an ordinary skirt.

2. A divided skirt comprising an upper portion shaped to fit the waist and hips of the wearer, and a pair of depending trunk portions joined at the crotch of the garment, each of said trunk portions comprising two pieces of material joined by seams extending, respectively, along the side of the garment on the outside of the trunk portion, and along the center of the trunk portion at the inside thereof, and said crotch being constructed and arranged to extend in a diagonal direction from front to rear of the garment so that the trunk portions substantially overlap each other both front and rear, the visible lines of

division between said trunk portions being substantially offset from the median line of the garment, each leg portion having a pleat extending along one side of one of said lines of division and an inverted pleat spaced from the other line of division, so that the garment presents the appearance of an ordinary skirt having a pair of pleats on opposite sides of its median line, both front and rear.

3. A divided skirt comprising an upper portion shaped to fit the waist and hips of the wearer, and a pair of depending trunk portions joined at the crotch of the garment, each of said trunk portions comprising two pieces of material joined by seams extending, respectively, along the side of the garment on the outside of the trunk portion, and along the center of the trunk portion at the inside thereof, and said crotch being constructed and arranged to extend in a diagonal direction from front to rear of the garment so that the trunk portions substantially overlap each other both front and rear, the visible lines of division between said trunk portions being substantially offset from the median line of the garment, each leg portion having a pleat extending along one side of one of said lines of division and an inverted pleat spaced from the other line of division, and tuck pleats leading upwardly from said lines of division and from said inverted pleats substantially to the waistband of the garment, so that the garment presents the appearance of an ordinary skirt having a pair of pleats on opposite sides of its median line, both front and rear.
